(57) **CLAIM**

The ornamental design for a machine for measuring surface shape and surface roughness, as shown and described.

DESCRIPTION

FIG. 1 is a front, top, right-side perspective view of the machine for measuring surface shape and surface roughness; FIG. 2 is a front-elevational view thereof; FIG. 3 is a top plan view thereof; FIG. 4 is a left-side elevational view thereof; FIG. 5 is a right-side elevational view thereof; FIG. 6 is a rear elevational view thereof; FIG. 7 is a bottom plan view thereof; and, FIG. 8 is a front, top, left-side perspective view thereof. The broken lines depict unclaimed parts of the machine, and thus form no part of the claimed design.
